CLAIM

The ornamental design for a bicycle safety reflector, as shown and described.

DESCRIPTION

FIG. 1 is a perspective view of the bicycle safety reflector embodying the design of the present invention;

FIG. 2 is a front elevational view thereof;

FIG. 3 is a rear elevational view thereof;

FIG. 4 is a side elevational view thereof, the side opposite being a mirror image of the side shown in FIG. 4;

FIG. 5 is a top plan view thereof;

FIG. 6 is a bottom view thereof; and,

FIG. 7 is a perspective view of a second embodiment thereof, wherein the only difference resides in the abutting of two bicycle safety reflectors.

FIG. 1.

FIG. 3.

FIG. 4.
